CONE OF SILENCE SIMULATOR

Charles J. Kennedy, Sun Valley, Calif., assignor to Collins Radio Company, Cedar Rapids, Iowa, a corporation of Iowa

Application April 2, 1952, Serial No. 280,089

1 Claim. (Cl. 35—10.2)

This invention relates to means for simulating a radio range in the vicinity of the station.

It is oftentimes desirable to train flight crews on the ground where their errors will not prove fatal and where the expense is much less than in the air. For example, the co-pending application entitled "Synthetic A/N Range," Patent Number 2,621,425, issued December 16, 1952, assigned to Collins Radio Company, discloses an A/N range simulator for a student.

That invention disclosed means for setting an A/N range station so that the student can orient himself with respect to the station. The present invention is a supplement to that one and relates to means for a build-up in the immediate vicinity of the station and a cone of silence over the station. Actual radio installations of A/N range stations have the characteristic that as the plane approaches the station, the signal builds up rapidly to a peak and then falls to a dead silence in a zone immediately above the station. This indicates to the pilot when he is directly over the station.

It is an object of this invention, therefore, to provide a synthetic build-up and cone of silence device for a synthetic A/N range station.

Further objects, features and advantages of this invention will become apparent from the following description and claims when read in view of the drawings, in which:

Figure 1 illustrates a portion of the circuitry of this invention;

Figure 2 illustrates a second portion of the circuitry;

Figure 3 is a graphic representation showing the aircraft's position with respect to the station; and

Figure 4 illustrates the gradual fade circuit of this invention.

With reference to Figure 3, let it be assumed that an aircraft P is located a distance R from a station S and that with respect to Cartesian coordinates the point P may be located with respect to the station S by ΔX and ΔY .

Figure 1 illustrates a ΔX computer 10 which continuously computes the distance ΔX . A ΔY computer 11 continuously computes the ΔY component. Such computers are well known to those skilled in the art but for illustration, the values of ΔX and ΔY may be set in manually by the instructor. The outputs of the ΔX and ΔY computer are furnished to amplifiers V₁ and V₂, respectively, through resistors R₁ and R₂.

The outputs of amplifier V₁ and V₂ are passed to second amplifiers V₃ and V₄ to obtain high level amplification. A battery E₁ is connected to the plates of the four amplifier tubes to supply the plate voltage.

A 400 cycle power supply 13 supplies an input to the primary 14 of a transformer which has a pair of secondaries 16 and 17 that each have their ends connected to the mid-point of secondaries of transformers 18 and 19.

The primary 21 of transformer 18 is connected to the plate of the tube V₃ and the primary 22 of transformer 19 is connected to the plate of tube V₄.

A pair of phase detectors are designated generally as

2

23 and 24, respectively, and each comprise a pair of diodes V₅, V₆, V₇ and V₈, which have their plates connected to opposite ends of the secondaries of the transformers 18 and 19. One end of the secondary 16 is connected between a pair of condensers C₁ and C₂ which are connected between the cathodes of tubes V₅ and V₆. One end of the secondary 17 is connected between condensers C₃ and C₄ which are connected between the cathodes of tubes V₇ and V₈.

10 Polarity reversing circuits 26 and 27 are connected to each phase detector 23 and 24 and each comprise four diode rectifiers which might be, for example, selenium diodes with two of the diodes connected in series with the phase detector outputs and two in parallel in an X fashion as shown. The outputs of the polarity reversing circuits 26 and 27 are connected together so that the largest signal will predominate. The output is connected to terminal 28.

Figure 2 shows the terminal 28 which is connected to a circuit comprising diodes 29 and 31 which have condensers C₅ and C₇ connected across them.

An audio signal generator 32 supplies an input to a pentode V₉ which has the circuit comprising the diodes 29 and 31 connected between its control grid and cathode. The circuit comprising the diodes 29 and 31 and condensers C₅ and C₇ has the characteristic that when the direct current input from the polarity reversing circuits 26 and 27 goes to zero the impedance of the circuit is very high, but when the direct current signal supplied to terminal 28 is positive, the impedance of the circuit is very low.

A gradual fade circuit 33 is also connected to the control grid 35 of variable mu pentode V₉ to vary its output in inverse proportion to the distance from the station.

35 The gradual fade circuit 33 is shown in detail in Figure 4. It comprises a battery E₂ which has its positive terminal connected to ground and its negative terminal connected to a resistor R_a. The other side of resistor R_a is connected to ground. A slide contact 41 engages resistor R_a and is controlled by a shaft 42 which has a knob 43 attached thereto. The contact 41 is connected to the output conductor of the gradual fade circuit 33. The knob 43 may be controlled manually by the instructor to simulate an approach to the radio station. It is to be particularly noted that the output of the gradual fade circuit 45 becomes more positive as the distance to station becomes smaller.

The plate of the pentode V₉ is connected to a transformer 34 which has the mid-point of its secondary connected to the terminal 28. A ring modulator circuit 36 is connected across the ends of the secondary. The ring modulator 36 is connected to the primary of a transformer 37 which has its secondary 38 connected to earphones 39 and 40. The earphones furnish the audible signal to the student.

55 The ring modulator circuit has the property of being balanced and hence transmits no signal from transformer 34 to transformer 36 when the voltage applied to terminal 28 is zero. When voltage is applied to terminal 28 as is the case when the aircraft is other than directly over the station, the ring modulator passes a signal proportional to this D. C. voltage. When the voltage at terminal 28 has reached a value of about .10 volt, further increases no longer bring about proportionate increases in audio signal level since the ring modulator reaches saturation. The D. C. voltage reaches this saturation level only a short distance from the station owing to high amplification in the ΔX and ΔY amplifiers.

60 It may be seen from the explanation above that the signal from the ring modulator circuit will be zero directly over the station and will increase sharply as the aircraft progresses away from the station until it reaches

a maximum value at a distance dependent upon the overall gain of the ΔX and ΔY amplifiers. This effect introduces the cone of silence simulation.

Action of diodes 29 and 31 in sharply increasing their effective resistance when the voltage applied to terminal 28 is zero, is utilized to provide variable attenuation such that when the output voltage of bridge rectifiers 26 and 27 drops as the station is approached, the audio signal level applied to transformer 34 through amplifier V_9 is rapidly increased. It is this increased signal which is attenuated by the ring modulator when its action commences still closer to the station.

Thus, it may be seen that the sequence of events is as follows: Starting from a point distant from the station, as the aircraft proceeds, less negative voltage is applied to variable mu amplifier V_9 causing its output to increase slowly as a radio signal would in an aircraft receiver having no AVC action. At a point close to the station, the amplifier outputs begin to drop as does the D. C. signal derived from those outputs. At a distance corresponding to approximately .5 volts D. C. on terminal 28, the resistance of diodes 29 and 31 begins to increase causing the audio signal to rise.

This rise continues until the voltage at terminal 28 drops to a level of .10 volt whereupon the ring modulator is no longer saturated and it begins to attenuate the audio signal. Attenuation increases as the voltage on terminal 28 drops until, at zero D. C. volts, almost no audio signal passes through the ring modulator circuit. As the aircraft passes over the station the reverse of the above action takes place with the ring again becoming unbalanced and passing signal up to the point of saturation and the

5 diodes circuit taking over and dropping the audio signal down to the distant level.

Although this invention has been described with respect to particular embodiments thereof, it is not to be so limited as changes and modifications may be made therein which are within the full intended scope of the invention, as defined by the appended claim.

I claim:

Means for simulating a radio range station in the vicinity of a cone of silence comprising, an audio signal generator, an electron tube receiving an output from said audio signal generator, a pair of computing means producing outputs corresponding, respectively, to the Cartesian coordinates of the simulated position relative to the station, a pair of phase detectors connected respectively to the outputs of the computing means, a pair of polarity reversing circuits connected to the outputs of the phase detectors so as to always produce one polarity, the outputs of the two polarity reversing circuits connected together so that the larger one dominates, a variable attenuating circuit connected to the control grid of said electron tube, the outputs of said polarity reversing circuits connected to said variable attenuating circuit, a ring modulator coupled to the output of said electron tube, and audible signal reproducing means coupled to the ring modulator.
